UNITED STATES PATENT OFFICE.

HAROLD H. ROBERTSON, OF SEWICKLEY, PENNSYLVANIA, ASSIGNOR TO ASPROMET COMPANY, OF PITTSBURGH, PENNSYLVANIA, A CORPORATION OF PENNSYLVANIA.

BUILT-UP ROOFING.

1,343,478.

Specification of Letters Patent. Patented June 15, 1920.

Application filed November 27, 1918. Serial No. 264,420.

To all whom it may concern:

Be it known that I, HAROLD H. ROBERTSON, a subject of the King of Great Britain, residing in Sewickley, in the county of Allegheny and State of Pennsylvania, have invented an Improvement in Built-Up Roofings, of which the following description, in connection with the accompanying drawings, is a specification, like characters on the 10 drawings representing like parts.

The present invention relates to a protective covering especially designed and adapted for roofs and other relatively flat parts of a building, and has for its object 15 to provide a superior and more durable protective covering for the purpose specified.

To this end the protective covering is composed of preferably a plurality of superimposed sheets or layers of paper or felt 20 capable of readily absorbing asphalt or like bituminous compositions, with which said layers are saturated to provide the protective covering with a maximum quantity of water-repellent material, and a layer or 25 sheet of asbestos paper or felt which is saturated with asphalt or other waterproofing material and which is opaque, dense and resistive to the actinic rays of the sun and to the action of acid and alkaline fumes and 30 gases, and which is applied to and united with the saturated layers of paper or felt to form a protective covering for the said saturated layers.

The felt and asbestos layers may and preferably will be separated from the roof and from each other by layers of asphalt of a higher melting point than the asphalt with which the said layers are saturated, which 35 layers of higher melting point asphalt serve 40 to cement the fibrous layers together and increase the water-repelling properties of the covering. The roof when made of gypsum, cement or like slabs may and preferably will be provided with a thin primary 45 coat of cold liquid asphalt, which serves to bind together loose particles of gypsum or cement on the surface of the roof and provides a better and more homogeneous foundation for the cementing asphalt, and also 50 serves as a filler for the said slabs whereby a better bond of the cementing layer of asphalt applied to the roof is obtained, and absorption by the roof slabs of the lighter oils of the cementing asphalt is prevented. The opaque, dense and resistive layer of as-

bestos serves to maintain the water-repellent asphalt with which the felt layers are saturated as well as the cementing asphalt, in a condition of maximum efficiency as a water-repellent for a maximum length of 60 time, with the result that a superior, and more durable covering for roofs and the like may be obtained.

The asbestos layer may and preferably will have applied to it a layer of cementing asphalt to which a layer of sand or other granular material is applied.

The particular features of this invention will be pointed out in the claims at the end of this specification. 70

The drawing represents a portion of a roof provided with a protective covering embodying this invention.

Referring to the drawing *a* represents a portion of a roof, which may be of wood, 75 metal or plastic material such as gypsum, concrete or the like. The roof *a* is provided with a protective covering comprising preferably a plurality of layers 10 of wool felt or like material capable of readily absorbing 80 asphalt or like bituminous material, said layers being herein represented as three in number and the saturating asphalt being represented by the stipple 12.

The wool felt layers 10 are laid one upon 85 the other on the roof *a* and are adhesively secured together by layers 13 of asphalt of a higher melting point than the saturating asphalt 12 and which may be designated cementing asphalt layers, and these saturated 90 wool felt layers are then covered by a layer 14 of opaque relatively dense material, such as asbestos paper or felt, which is waterproofed in any suitable manner, preferably by saturating the same with asphalt 12, and 95 the asbestos layer 14 may and preferably will have applied to it a layer 15 of cementing asphalt to which a coating 16 of sand or like granular material is applied.

It is preferred to first apply to the roof 100 *a* especially when made of gypsum, cement or like material, a thin priming coat 17 of cold liquid asphalt, a portion only of which is shown in the drawing to enable it to be distinguished from the cementing layer 13 105 applied to it. In practice the asphalt comprising the cementing layers 13 is hot when applied.

The protective covering described forms an effective and superior protection for the 110

- roof *a*, as the asphalt or bituminous material is present in a maximum quantity and its water-repellent properties are available as a protection for the roof for a maximum length of time, owing to the fact that the wool felt layers readily absorb the asphalt and consequently carry a maximum quantity of the same, and the layer of asbestos felt or paper, being opaque, dense, and resistive to fire and to acid and alkali gases and fumes, protects the water-repellent layers of saturating as well as the cementing asphalt from the action of the actinic rays of the sun, from acid and alkali gases and fumes, and also prevents loss of the volatile ingredients in the asphalt. Additional protection is afforded by the gritty layer 15.
- It will readily be seen that the individual layers of wool felt and asbestos paper or felt may be prepared in the factory, shipped to the job and applied one to the other on the roof, and when the covering has thus been built up, the coating of gritty material may be readily applied thereto, with the result that the roof is provided with a covering which is fire-resisting, affords superior protection for the roof against the weather and atmospheric conditions, and which is of maximum durability.
- 30   Claims:
1. A protective covering for roofs and the like comprising a plurality of superimposed layers of wool felt saturated with asphalt, and a layer of asbestos felt saturated with asphalt and superimposed upon the said wool felt layers, and a layer of

gritty material adhesively affixed on said asbestos layer.

2. A protective covering for roofs and the like comprising a plurality of superimposed layers of wool felt saturated with asphalt, and a layer of asbestos felt saturated with asphalt and superimposed upon the said wool felt layers. 40

3. A protective covering for roofs and the like, comprising a layer of relatively high melting point bituminous material, a layer of fibrous material saturated with a lower melting point bituminous material and applied to said layer of relatively high melting point, a layer of relatively high melting point bituminous material applied to said fibrous layer, and a waterproofed and denser layer of fibrous material which is resistive to acids and alkali fumes and the actinic rays of the sun superimposed on said saturated fibrous layer and cemented thereto by the interposed layer of relatively high melting point bituminous material. 45 50

4. A protective covering for roofs and the like, comprising a priming coat of liquid asphalt, a cementing layer of asphalt applied to said priming coat, a layer of fibrous material saturated with asphalt and applied to the layer of said cementing asphalt, a layer of cementing asphalt applied to said saturated fibrous layer, and a waterproofed layer of asbestos felt or paper applied to the second mentioned cementing asphalt layer. 60

In testimony whereof I have signed my name to this specification. 70

HAROLD H. ROBERTSON.
